UNITED STATES PATENT OFFICE.

ALONZO JANES, OF BEIRNE, ARKANSAS.

LOCK.

1,228,445.

Specification of Letters Patent.

Patented June 5, 1917.

Application filed August 3, 1916. Serial No. 113,003.

To all whom it may concern:

Be it known that I, ALONZO JANES, a citizen of the United States, residing at Beirne, in the county of Clark and State of Arkansas, have invented a new and useful Lock, of which the following is a specification.

The device forming the subject matter of this application is a lock, and the invention aims to provide novel means whereby the 10 tumblers of the lock may be mounted and actuated.

A further object of the invention is to provide a lock which will be difficult to pick or tamper with feloniously.

15 It is within the province of the disclosure to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawing:—

30 Figure 1 is a sectional view showing a lock embodying the present invention, parts appearing in elevation;

Fig. 2 is a cross section on the line 2—2 of Fig. 1;

35 Fig. 3 is a cross section on the line 3—3 of Fig. 1;

Fig. 4 is a front elevation of a lock embodying the present invention;

Fig. 5 is a perspective view showing one 40 of the locking bolts;

Fig. 6 is a perspective view showing one of the tumblers;

45 Figs. 7 and 8 are perspective views delineating certain of the connecting elements in the lock; and

Fig. 9 is a detail view illustrating the means whereby certain of the drill-impeding balls are mounted in the lock.

Fig. 10 is a side elevation of the key.

50 Fig. 11 is a perspective view showing the barrier.

In the drawings, the numeral 1 indicates a tubular casing including a front plate 2. Projecting rearwardly from the front plate 55 2 and connected with the front plate and with the casing is an upstanding fin 3. The bore of the casing 1 is denoted by the nu-

meral 4 and is enlarged at its forward end to form a recess 18. In the fin 3 and in the casing 1 are formed vertical passages 6. 60 Slidable in the passages 6 are locking bolts 7. Mounted in the passages 6 above the locking bolts 7 and bearing upon the upper ends of the locking bolts are compression springs 9. The upper ends of the springs 9 65 are engaged by a cap plate 10 united with the fin 8 by means of securing elements 11. The springs 9 tend to force the locking bolts 7 inwardly.

70 Journaled in the bore 4 of the casing 1 is a barrel 12 having a flange 14 received for rotation in the recess 18 of the casing 1. Applied to the forward end of the barrel 12 is an auxiliary plate 15. The plate 15 may be held in place by securing elements 16, preferably 75 screws, extended through the flange 14 of the barrel 12, from the rear toward the front, so that they cannot be removed from the front of the lock. Balls 20 are molded into the front plate 2. Balls 21 are mounted 80 to rotate between the auxiliary plate 15 and the flange 14 of the barrel 12.

85 The auxiliary plate 15 has a narrow key hole slot 22. At the rear of the key hole slot 22, a recess 23 is formed in the auxiliary plate 15, and a wear plate 24 is mounted in the recess 23. The wear plate 24 has a key hole slot 25 registering with the key hole slot 22 in the auxiliary plate 15. In the forward end of the barrel 12 to the rear of the wear plate 24 is a laterally enlarged chamber 26 best shown in Fig. 3. A barrier 90 27 is mounted to swing in the chamber 26, crosswise of the barrel 12 and has a beveled surface 27a. A pivot element 29 unites the lower end of the barrier 27 with the barrel 12. The barrier 27 is swung laterally so as to close the key hole slots 25—22, by means of a compression spring 28 interposed between one edge of the barrier and the barrel 95 100 12. In the barrel 12 there are molded balls 31. It is necessary to locate the balls 31 to the rear of the balls 20 and 21, owing to the presence of the chamber 26. The barrel 12 has a key hole slot 32 registering with the key hole slots 22 and 25. Communicating with the key hole slot 22 in the barrel 12 are radial passages 33 aligned with the passages 6 in the casing 1. Tumblers 34 are mounted for right line sliding movement in the passages 33. In Fig. 2 of the drawings, the line of abutment between the tumblers 34 and the locking bolts 7 is indicated at 36. Journaled in the inner ends of the tumblers 34

105 110 115

are balls 37 adapted to coact with the key, when the same is thrust into the key hole slot.

In the rear end of the barrel 12 there is 5 formed a notch 38 adapted to receive lugs 39 at the end of a connecting plate 40. A ring 41 is applied to the rear end of the barrel 12 and overlaps the lugs 39 on the plate 40 to hold the plate on the barrel 12, 10 so that when the barrel is rotated, the plate will be rotated also. The ring 41 is attached by securing elements 42 to the rear end of the barrel 12.

The numeral 43 designates a casing having 15 an opening 44 in its rear wall, the casing including an annular rib 45 projecting into the opening. At 46 there appears a ring made up of an inner part 47 and an outer part 48 held together by screws 49.

20 The parts 47 and 48 coöperate to define a groove 50 which receives the rib 45, and thus the ring 46 is journaled for rotation on the casing 43. The parts 47 and 48 are provided with a slot 51 in which one end 25 of the plate 40 is received. The construction, therefore, is such that the casing 43 may be moved toward and away from the casing 1, to accommodate doors of different thicknesses. The outer part 48 of the ring 30 46 is provided with ears 52 adapted to coöperate with cross arms 53 carried by stems 54 which may constitute a part of an ordinary locking bolt. The cross arms 53 are adapted to be engaged by a head 55 on a 35 stem 56 constituting a part of a knob 57 journaled in the casing 43.

The numeral 58 designates a flat key having serrations or teeth 59.

In practical operation, the key 58 is thrust 40 through the key hole slots 22 and 25 and enters the key hole slot 32 of the barrel 12, the beveled part 27^a of the barrier 27 permitting the barrier to be thrust to one side by the key. The balls 37 on the inner ends 45 of the tumblers 34 ride on the serrated edge 59 of the key and facilitate the insertion of the key. When the key is in place, all of the tumblers 34 and the locking bolts 7 are pushed outwardly until the lines of abutment 36 between the tumblers and the locking bolts are alined with the wall of the bore 4 of the casing 1. Then, the barrel 12 50 may be rotated by the key. When the barrel 12 is rotated, the plate 40 is rotated, the ring 55 46 is rotated, and the lugs 52, coacting with the cross arms 53 will actuate the locking bolt of which the stems 54 constitute a part.

When the key 58 is withdrawn from the key hole slot, the tumblers 34 and the locking bolts 7 move inwardly into the positions shown in Fig. 2, the locking bolts 7 coacting with the barrel 12 to prevent the same from rotating. When the key is completely with-

drawn, the barrier 27 swings over into the position of Fig. 3, under the action of the 65 spring 28 and closes the key hole.

The function of the balls 31, 20 and 21 will now be set forth. Owing to the provision of these balls, it will be extremely difficult to drill into the lock and tamper with 70 the same. If the drill strikes the hard metal balls, the balls will key and hold the drill, so that the same will be likely to be snapped off.

It is to be observed that the tumblers 34 are of different lengths, and this fact, 75 combined with the fact that the serrations 59 on the key 58 may be variously fashioned, renders the unwarranted opening of the lock difficult of accomplishment.

The device forming the subject matter of 80 this application is adapted to be used primarily but not exclusively on a door lock.

The tumblers 34 and the locking bolts 7 are of rectangular cross section, which prevents them from rotating axially. Because 85 the tumblers or the locking bolts cannot rotate, friction is reduced.

Having thus described the invention, what is claimed is:—

A lock comprising a casing having a recess at its forward end; a barrel rotatable in the casing and provided at its forward end with a flange which is rotatable within the recess, the barrel having a key hole slot and being provided at its forward end with a laterally enlarged chamber communicating with the key hole slot; a barrier pivoted to the barrel and mounted to swing in the chamber transversely of the key hole slot; spring means in the chamber for maintaining the barrier in closed position with respect to the key hole slot; an auxiliary plate secured to the flange and constituting a closure for the forward end of the chamber, the auxiliary plate being rotatably mounted in 105 the recess and having a key hole slot alined with the key hole slot of the barrel, the barrier having a beveled key-engaging portion alined with the key hole slot of the auxiliary plate; a tumbler slidable in the barrel transversely of the barrel and accessible from the key hole slot of the barrel; and a locking bolt slidable in the casing and alined with the tumbler, the tumbler constituting means for moving the locking bolt outwardly, to 110 aline the inner ends of the tumbler and the bolt with the outer surface of the barrel, whereby the barrel may be rotated.

In testimony that I claim the foregoing as my own, I have hereto affixed my signature in the presence of two witnesses.

ALONZO JAMES.
